(57) **CLAIM**

The ornamental design for a building element, as shown and described.

DESCRIPTION

The design application is related to U.S. Design patent application Ser. No. 29/395,162, which application is filed concurrently with this application on Sep. 21, 2007, and U.S. Design patent application Ser. No. 29/295,176, which application is filed concurrently with this application on Sep. 21, 2007.

FIG. 1 is a perspective view of the building element of the present design;

FIG. 2 is a front elevation view thereof;

FIG. 3 is a back elevation view thereof;

FIG. 4 is a top plan view thereof; and the bottom plan view is a mirror image of this view, and therefore has been omitted; and,

FIG. 5 is a right side elevation view thereof, and the left side elevation view is a mirror image of this view, and therefore has been omitted. The claimed design is broken on the bottom and left sides to indicate indefinite length.

The fragmented lines are for illustrative purposes only and form no part of the claimed design. The fragmented lines indicate an indefinite length and width.
